By Attorney

UNITED STATES PATENT OFFICE.

JASPER VAN SCHOONEVELD, OF NEW YORK, N. Y.

DAYLIGHT REFLECTOR.

Application filed September 13, 1918. Serial No. 253,940.

To all whom it may concern:

Be it known that I, JASPER VAN SCHOONEVELD, a citizen of the United States, residing at New York city, in the county of New York, State of New York, have invented certain new and useful Improvements in Daylight Reflectors; and I do hereby declare the following to be a full, clear, and exact description of the invention, such as will enable others skilled in the art to which it appertains to make and use the same.

This invention relates to new and useful improvements in reflectors and particularly to reflectors which are adapted to reflect light into rooms which do not have windows positioned to receive the direct rays of light.

One object of the present invention is to provide a novel and improved device of this character which will not only reflect into the room, but which will be so arranged that the occupants may readily see thereunder.

Another object is to provide a novel and improved device of this character which can be readily applied to and adjusted with relation to a window, whereby the light can be reflected into the room to the degree desired.

Other objects and advantages will be apparent from the following description when taken in connection with the accompanying drawing.

In the drawing:

Figure 1 is a front elevation of a window equipped with my improved reflector.

Figure 2 is a top plan view of the same.

Figure 3 is a vertical sectional view taken on the line 3-3 of Figure 1.

Referring particularly to the accompanying drawing, 10 represents a pair of brackets which are secured to extend outwardly from the side stiles 11 of the window frame 12. The outer end of each of the arms is formed with an eye 13 for the reception of a laterally extending pin 14 carried by the side of the reflector frame 15. Secured in this frame 15 is a sheet of material 16 which will readily reflect daylight and having the back of same covered so that printing of advertisements can be produced on the said

back and be seen from below. A chain 17 is secured to one of the upper corners of the reflector frame, the other end being arranged for adjustable engagement with a removable pin or hook 18, carried by the side of the window frame.

This device is particularly adapted for use in buildings which are very tall and which have central light shafts for the windows looking out onto said shafts. The light comes vertically down the shaft, and

the lower rooms of the building do not get any direct light, in fact get very little light at all. With the device forming the subject-matter of the present application, the reflector frame can be adjusted to such an angle that the light from the upper end of the light shaft can be reflected into the lower rooms, with sufficient strength to obviate the use of artificial lighting. Furthermore, the view of the occupants, out into the shaft, is not obstructed by the reflector, by reason of the fact that the reflector is capable of adjustment in such a way as to leave sufficient room for observation from within.

While the primary object is to reflect light into dark rooms, as above explained, the device may also be used in a window over the entrance of a dwelling to permit the occupants to see anyone on the steps. The outer face of the reflector is adapted to have various advertisements painted or otherwise applied thereon.

The reflector may be tilted into such position that its upper edge lies against the window frame and its lower edge projects outwardly, the window sash being lowered to a point adjacent the upper edge of the reflector, whereby the reflector constitutes a transparent awning which will deflect rain so that the rain will not enter the room. At the same time, light will pass through the reflector into the room, and the occupants of the room still be permitted to observe external objects through the window beneath the reflector.

What is claimed is:

The combination with a window frame of a pair of brackets, fastened to the window

frame and extending externally thereof, a frame, having the intermediate portions of its sides pivotally mounted upon the brackets, said frame being covered with suitable light reflecting material, a chain, one end being connected to the top of the frame, the other end to be engaged with means carried by the side of the window frame to regulate

the position of the frame for reflecting the day light into the room.

In testimony whereof, I affix my signature in the presence of two witnesses.

JASPER VAN SCHOONEVELD.
